PERFORATING AND TRIMMING MECHANISM

Filed Dec. 17, 1928

UNITED STATES PATENT OFFICE

HAROLD LANGLEY BLOOD, OF HINSDALE, ILLINOIS, ASSIGNOR TO WESTERN ELECTRIC COMPANY, INCORPORATED, OF NEW YORK, N. Y., A CORPORATION OF NEW YORK

PERFORATING AND TRIMMING MECHANISM

Application filed December 17, 1928. Serial No. 326,475.

This invention relates to perforating and trimming mechanisms, and more particularly to an apparatus for simultaneously punching the grid of a telephone transmitter mouthpiece and trimming the molding fin from its edges.

In manufacturing molded transmitter mouthpieces, a molding fin is left on the edge of that portion of the mouthpiece having the largest peripheral dimension, and the bridge in the portion between the throat of the mouthpiece and the diaphragm of the transmitter is not completely apertured. This necessitates removing the molding fin and 10 punching out the material remaining in the partially formed holes after the mouthpiece is taken from the molding machine. It has heretofore been the practice to take the molded mouthpiece to a turning or trimming device 20 vice to remove the molding fin, and subsequently place the mouthpiece in a punch press to complete the holes in the bridge portion of the mouthpiece.

An object of this invention is the provision 25 of an efficient, simple, and easily operated apparatus for quickly perforating and trimming an article.

In accordance with one embodiment, the invention contemplates the provision of a rotatable trimming device, the cutting edges of 30 which rotate about a supporting member upon which the mouthpiece may be positioned and a plurality of perforating members reciprocable into and out of engagement with the 35 mouthpiece positioned on the supporting member to punch through the material remaining in the partially formed holes in the bridge and move the mouthpiece past the cutting tools to trim the molding fin therefrom.

This and other objects will be apparent 40 from the following detailed description when considered in conjunction with the accompanying drawings, wherein

Fig. 1 is a side elevational view partly in section of a punching and trimming device embodying the features of this invention;

Fig. 2 is a sectional view of a telephone 50 mouthpiece previous to the removal of the

molding fin and the excess material at the bridge portion, and

Fig. 3 is an enlarged view of the perforating die shown partly in section.

Referring now to the drawings wherein like reference numerals designate similar parts throughout the several views, the numeral 9, designates generally a punching and trimming device embodying the features of this invention. A housing 10 encloses a tool holder 11 which is rotatable about a sleeve 13, positioned in the housing by means of a cap 14 threaded on the end of the sleeve and engaging an annular shoulder 15 formed on the housing, and annular spacers 17 and 18 cooperating with inner bearing races 19 and 21 which engage annular shoulders 22 and 23, respectively, formed on the sleeve.

The tool holder is rotatable about the sleeve on ball bearings 25—25 and 26—26 mounted in inner bearing races 19 and 21 respectively, and outer bearing races 27 and 29, respectively, attached to the rotatable tool holder. A belt 30 driven by a motor, not shown, engages a pulley formed on the tool holder and furnishes power to rotate the tool holder which has a pair of tools 33—33 clamped to projections 34—34 formed on an annular shoulder thereof. The tools are secured to the projections 34—34 by means of clamps 35—35 secured to the projections by screws 37—37 threaded in the projections and passing through apertures 38—38 in the clamps.

The sleeve 13 has a key way 39 formed therein in which a key 41 fixed to a shaft 42 is slidable. A spring 40 positioned between the cap 14 and a headed member 43 threaded in the shaft 42, normally urges the member 43 into engagement with the bottom of the sleeve 13 and holds a mouthpiece holding member 45 formed on the end of the shaft 42 above the tools mounted on the tool holder. The mouthpiece holding member is designed to receive an inverted telephone mouthpiece, of the type shown in Fig. 2, having partially formed holes 46 from which the material shown at 47—47 must be removed and having a molding fin 49 which also must be removed.

In order to prevent the mouthpiece from rotating when it is moved into engagement

with the tools, a plurality of pins 50—50 positioned in apertures 51—51 in the upper end of the shaft 42 are provided for engaging the partially formed holes in the mouthpiece. 5 These pins are slideable in the apertures 51 and are normally urged upwardly to engage the partially formed holes in the mouthpiece by a spring 53 positioned in a cavity 54 in the shaft 42 and between a disk 55 on which 10 the pins rest and a rod 57 held in the cavity by the headed member 43.

A cover plate 58 having a circular aperture 59 therein through which a mouthpiece may be passed to position it on the mouthpiece 15 holding member, is formed integral with a sub-base 61 secured to the housing 10 on which sub-base a standard 62 for supporting perforating apparatus, designated generally by the numeral 63, is mounted. The standard 20 is secured to the sub-base by means of bolts 65—65 passed through apertures 66—66 in a base 67 of the standard and threaded in the sub-base and has at its upper end a vertically disposed cylindrical sleeve 69 formed integral 25 therewith in which is slidably mounted a perforator actuating shaft 70. The perforator actuating shaft has an aperture 71 therethrough in which a bolt 73 may be positioned for securing a perforating die 74 to the lower 30 end of the perforator actuating shaft.

Vertically reciprocable motion is imparted to the perforator actuating shaft by a manually controlled lever 75 pivotally mounted on the standard at 77 and having 35 a handle 78 formed at one end thereof and a counter balance 79 adjustably secured to the other end thereof by means of a set screw 81. This pivoted lever has a projection 82 formed thereon to which a link 83, connected by a pin 86 to a shoulder 85 of the perforator actuating shaft, is pivotally mounted by means of a second pin 87.

The perforating die 74 has a cylindrical portion 89 in which the bolt 73 is threaded 45 and a second cylindrical portion 90 in which a recess 91 and a plurality of apertures 93—93 are formed. A key 94 which engages the slots 95 and 97 formed in the perforator actuating shaft and the perforating die, respectively, is secured to the perforating die 50 by a screw 98. This key serves to accurately position the perforating die on the perforator actuating shaft so that perforating pins 99 carried by the die 74 will register with 55 the partially formed holes 46 in the telephone mouthpieces.

The perforating pins are mounted on the cylindrical portion 90 of the perforating die by means of two plates 101 and 102, one 60 of which, 101, has a plurality of apertures 103—103 through which the pins may be passed until the heads 105—105 of the pins 99—99 engage beveled edges 106—106 formed in the apertures 103—103. The 65 plates 101 and 102 are secured in the recess

91 of the cylindrical portion 90 by screws 107—107.

A stripping plate 109 is slidably mounted on the pins 99—99 and is normally urged downwardly by springs 110—110 and is restrained from movement downwardly beyond a predetermined point by bolts 111—111 secured to the stripping plate and engaging shoulders 113—113 in apertures 93—93. The springs 110—110 which urge 75 the stripping plate downwardly are positioned between the stripping plate and shoulders 114—114 in the apertures 93—93 and encircle the bolts 111—111.

It is believed that a better understanding 80 of this invention will be had by reference to the following description of the operation thereof. In the description of the operation it has been assumed that the tools 33—33 are being rotated by the belt 30. An unfinished mouthpiece may be positioned on the mouthpiece holding member by setting it thereon and rotating it until the pins 50—50 register with partially formed holes 46—46 and are forced into the partially formed 85 holes by the spring 53 to secure the mouthpiece against rotation.

The mouthpieces having been positioned 90 on the mouthpiece holding member, handle 78 may be moved downwardly to move the perforating die into engagement with the mouth piece and force it against the action of spring 40, past the constantly rotating tools 33—33 which will remove the molding fin 49. Continued movement of the handle 100 downwardly will cause the bottom of the mouthpiece holding member to engage the upper surface of the sleeve 13 at 115 and cause the perforating pins to punch the remaining material from the partially formed 105 holes 46—46.

The handle 78 may then be moved upwardly allowing the spring 40 to move the mouthpiece holding member up until the mouthpiece is above the tools 33—33. Simultaneously therewith the stripping plate 110 will be moved downwardly on the perforating pins by the springs 110—110 to strip the mouthpiece from the perforating pins 115 whereupon the mouthpiece may be removed and the operation repeated.

Although this invention has been described with reference to punching and trimming telephone mouthpieces, it will be understood that it is applicable to the manufacture of many other types of articles and should be limited only by the scope of the appended claims.

What is claimed is:

1. Apparatus for punching and trimming 125 an article comprising means for supporting the article, spring actuated means for securing the article against rotation, tools rotatable about the supporting means for trimming the article, means for moving the article 130

into engagement with the tools, and means cooperating with and actuated by said last mentioned means for perforating the article.

2. Apparatus for punching and trimming an article comprising means for positioning the article, means for securing the article on the positioning means, tools rotatable about the positioning means for trimming the article, a plurality of perforating members, 10 means for actuating the perforating members and moving the article into engagement with the tools, and means for stripping the article from the perforating members after it has been perforated.

15 3. Apparatus for punching and trimming an article comprising a reciprocable article holding member, an annular tool holder rotatable thereabout, tools mounted on the tool holder, resilient means for normally holding 20 the article holding member in a predetermined position, means for securing an article on the article holding member, means for compressing the spring to move the article past the tools to trim the edge therefrom, and 25 means actuated by the last mentioned means for perforating the article.

4. Apparatus for punching and trimming an article comprising a sleeve, tools rotatable thereabout, a shaft slidable longitudinally 30 within the sleeve, means mounted on the shaft for securing an article positioned thereon against rotation, means for moving the shaft longitudinally of the sleeve to bring the article into engagement with the tools, perforating pins cooperating with the last mentioned means for perforating the article, and 35 a spring pressed stripping plate slidable on the perforating pins for stripping the article from the pins.

40 5. An apparatus for punching and trimming an article comprising a sleeve, an article positioning shaft slidable longitudinally of the sleeve, a tool holding spindle rotatable about the sleeve, means for rotating the 45 spindle, a spring normally holding the article positioning shaft in a predetermined position, resilient members positioned in the article holding shaft for securing an article thereto, means for compressing the spring, 50 perforating means carried by the last mentioned means for perforating the article, and a stripping plate slidable on the perforating pins for removing the perforated article therefrom.

55 6. Apparatus for punching and trimming an article, comprising a plurality of rotatable tools, means for supporting the article, means for moving the article past the tools to trim the edges of the article, perforating 60 pins carried by the last mentioned means for perforating the article, and a resiliently mounted stripping plate slidable on the perforating pins for stripping the article from the pins after it is perforated.

65 7. Apparatus for punching and trimming

an article comprising yielding means for supporting the article and for securing it against rotation, a tool rotatable about the yielding means for trimming the article, means for moving the article into engagement with the 70 tool, and means actuated by said last mentioned means for perforating the article.

In witness whereof, I hereunto subscribe my name this 4th day of December, A. D. 1928.
